UNITED STATES PATENT OFFICE.

SAMUEL C. BEAMER, OF MARSHALLTOWN, IOWA.

EGG-TRAY.

1,344,019.

Specification of Letters Patent. Patented June 22, 1920.

Application filed April 24, 1919. Serial No. 292,258.

To all whom it may concern:

Be it known that I, SAMUEL C. BEAMER, a citizen of the United States, residing at Marshalltown, in the county of Marshall 5 and State of Iowa, have invented a new and useful Egg-Tray, of which the following is a specification.

The present invention relates to egg trays for incubators, the object being to provide 10 a tray which will permit the eggs being turned or rotated from time to time so that the entire surface of the same may be subjected to the heat of the incubator.

A further object of the invention is to 15 provide a tray which may be used in connection with any conventional type of incubator and which may be operated without any danger of breaking the eggs.

An additional object of the invention is 20 to provide an egg turner of this character which is simple in construction, consists of few parts, and which may be manufactured and sold at a minimum cost.

With the above and other general objects 25 in mind, the invention consists of combinations of elements, arrangements of parts, constructions and operations and general assemblage which will be hereinafter specifically set forth and defined in the appended 30 claims, one embodiment of the invention being illustrated in the drawings, wherein:—

Figure 1 is a top plan view of an egg tray constructed in accordance with my invention:

Fig. 2 is a bottom plan view of the same; 35 and

Fig. 3 is a vertical cross section taken on line 3—3 of Fig. 1.

Referring to the drawings wherein like 40 characters of reference designate like parts in all the views, the numeral 5 denotes a rectangular tray to which is secured a sheet of reticulated material 6. Extending across the frame and secured to its opposite sides 45 centrally of their ends is a bar 7.

Parallel bars 8 extend parallel with bar 7 at opposite sides of the frame and disposed within the same. Pairs of bowed egg-supporting bars or tracks 9 extend at right- 50 angles to the bars 8 and are secured to the central bar 7, each pair of bars being spaced apart to prevent the eggs contacting. The

eggs are adapted to be supported on these bars to allow the same to be rolled.

Secured to the inner face of one of the 55 sides of the frame and above the adjacent bars 8 is a longitudinal strip of padding with which the eggs are adapted to contact. Vertical guide grooves 11 are formed in the opposite side bars of the frame at the end 60 opposite the padded end which receive a rail 12 having a strip of padding 13 thereon, this rail being adapted to be inserted in the guide grooves 11 when a set of eggs of small diameter is being hatched in the incubator. 65

Secured to the central rail 7 at its opposite ends is a pair of rockers 14 which allow the frame or tray to be tilted to permit the eggs to roll to one side thereof, the operator 70 tilting the frame at the opposite side, the frame remaining in this position until the operator has tilted the tray from the opposite side to cause the eggs to roll in an opposite direction.

This disclosure is merely illustrative and 75 it is to be understood that the same is to be modified in many respects and that such limits of modification are only governed by what is claimed.

What is claimed is:—

1. In a device of the class described, a tray; a track extended between oppositely disposed portions of the tray and bowed downwardly symmetrically from said portions of the tray to the longitudinal center 85 of the tray; stops on said portions of the tray at the ends of the track; and a depending rocker on the tray adjacent the longitudinal center of the tray.

2. In a device of the class described, a tray 90 including side walls; a bar extended across the tray adjacent the longitudinal center of the tray; cleats carried by said walls of the tray and having their upper surfaces disposed above the upper surface of the bar; 95 and rails having their ends supported on the cleats, the rails being downwardly bowed to coöperate with the bar and being secured to the bar.

3. In a device of the class described, a 100 tray including side walls; a bar extended across the tray adjacent the longitudinal center of the tray; cleats mounted on said walls of the tray and having their upper

surfaces disposed above the upper surface of the bar; rails having their ends supported on the cleats, the rails being downwardly bowed to coöperate with the bar and being secured to the bar; and stops located above the cleats and located at the ends of the rails, one of said stops being removable to permit the rails to be mounted on the cleats.

In testimony that I claim the foregoing as my own, I have hereto affixed my signature in the presence of two witnesses.

SAMUEL C. BEAMER.
